UNITED STATES PATENT OFFICE.

HENRY DETREUX AND BERNARD LOVATT, OF PHILADELPHIA, PENNSYLVANIA.

DESIGN FOR A PUZZLE.

51,720.

Specification for Design.

Patented Feb. 5, 1918.

Application filed November 22, 1917. Serial No. 203,455. Term of patent 3½ years.

To all whom it may concern:

Be it known that we, HENRY DETREUX and BERNARD LOVATT, both citizens of the United States, residing in the city and county of Philadelphia, State of Pennsylvania, have invented a new, original, and ornamental Design for Puzzles, of which the following is a specification, reference being had to the accompanying drawing, forming part thereof.

Copies of this patent may be obtained for five cents each, by addressing the "Commissioner of Patents, Washington, D. C."

The figure is a plan view of a puzzle, showing our new design.

We claim:

The ornamental design for a puzzle, as shown.

HENRY DETREUX.
BERNARD LOVATT.
